UNITED STATES PATENT OFFICE

ERICH LEHR, OF NEW YORK, N. Y.

CLIP CONSTRUCTION

Application filed September 1, 1931. Serial No. 560,547.

The present invention relates to clip construction in general and particularly to the kind adapted to suspend an article, while itself being secured to a suspending element.

The prime object of my invention is to provide a simple, inexpensive and effective device of this kind, by means of which articles, as for instance clothes, wet wash, wearing apparels, curtains or the like may be readily hung up from a clothes line or other suspension means without coming in contact with the latter, and to which my device may be readily attached or with which it may be associated prior to securing articles thereto.

Another object of my invention is to provide such clips with broadened or enlarged engaging surfaces so as to securely hold an article therebetween.

Another object of my invention is to provide such device in a manner, whereby an article to be suspended therefrom will not come in direct contact with the suspension means, to which my device is attached.

The foregoing and still further objects of my invention will become more fully apparent from the following description and the accompanying drawing, forming part of my disclosure, but by no means intended to limit the same to the actual showing, and in which

Fig. 1 illustrates one of the preferred forms of my device shown suspended from a cord or a clothes line.

Fig. 2 is a similar device with one of the features left out.

Fig. 3 shows a modified form of my device intended for suspension from a curtain rod or the like.

Fig. 4 is still another modification of my device, similar to that shown in Fig. 3, but of a more diminutive size.

Referring now to the figures, numeral 10 denotes a suspension element in the form of a rod, cord, clothes line, nail or other form, to which my device is attached.

In Figs. 1 and 2 the construction of the latter resembles a hair pin, although the material used is considerably stouter than hair pin wire. The device consists of a suspension end 11, composed of two legs 12, the up-

per ends of which are undulated, as indicated at 13. This undulation serves for the purpose of firmly gripping the suspension element 10 between legs 12.

The ends of the latter are bent toward one another at 14 and continue at 15, forming connections between the legs and the depending jaw ends 16 of the device, the jaws 17 of which are broadened, so as to enlarge the article engaging surfaces.

As will be clearly seen from these figures, legs 12 form a continuation of jaws 17 and cross one another. In Figure 1 the crossing point of members 15 is accentuated by the application of a ring 18, which is loosely mounted at the crossing point and is intended to hold the two leg portions of the device against a sidewise movement.

The upper or suspension ends of the device is connected by means of a link 19 engaging the two legs 12 and which is adapted to be shifted upwards, as indicated in broken lines, or into the bends 14 of the device for opening and closing the jaws, respectively. This link not only serves for the operation of the device but also is intended to hold it against side movement when ring 18 is omitted, as is the case in Figure 2.

The material used for making the device is preferably rust-proof wire, so as to enable the user to hang wet wash from the device without fear of causing rust spots thereon. The construction shown in Figures 1 and 2 is intended for permanently suspending the device from a clothes line or the like, which is passed through the upper portion of the clip before the latter is put to use.

In Figures 3 and 4 a hinge construction of my device is shown, which permits the attachment of the clip to already existing suspension elements, and enables the user to secure the clips individually at any point of such suspension element.

Referring to Figure 3 there will be again seen leg portions 12', made of resilient material and terminating at their upper ends into adjacent lips 20 and 21 which normally stand apart. Lip 21 is built out into a lug 22 and is pierced to receive a spring closure 23, adapted to swing from one edge of the lips, over

their tops and to their other edge, whereby the lips are drawn together, as illustrated.

Extending downwards from legs 12' there are connecting pieces 15', which are hinged together at 24. Below connecting pieces 15' there are again provided jaw members 16' terminating in broadened jaws 17', which are shown in this case specially formed, but which may be constructed similarly to the

10 manner employed in Figure 1.

When spring closure 23 is opened, leg portions 12' may swing out, as will jaws 17'.

When the leg portions are brought around a suspension element, spring closure 23 is closed 15 and bears with its long, indented sides against the sides of lips 20 and 21, thereby holding them against opening and at the same time pressing the jaws together. Prior to closing the leg portions, any article may be slipped 20 between jaws 17' and firmly held by them, due to the resiliency of the clip material.

A similar construction is illustrated in Figure 4, in which instead of flat stock, employed in the construction shown in Figure 3, resilient wire material is used. In this modified form there are again constructed leg members 112 and 112', the former provided with a notch 25, while leg 112' terminates in a loop 26 holding a link 27. The latter is adapted to slip over the end of leg member 112, and to engage notch 25 thereof.

From legs 112 and 112' there extend downwardly from bends 14' connecting members 115, which are crossing one another and are 35 hinged at 24'. Connecting members 115 terminate in jaw members 116, which are equipped with broadened jaws 117, in this case in the form of bars disposed at right angles to jaw members 116, which may, however, be constructed in the same manner as 40 shown in Figures 1 and 2.

The operation of the device shown in Figure 4 is practically the same as that described in connection with Figure 3, with the exception that the wire clip is intended for suspending small articles and for being suspended from a thinner element 10.

While I have shown specific forms of my device, be it understood that modifications, 50 and changes may be made therein as is clearly evident from the different constructions illustrated, and I therefore reserve for myself the right to make such changes and improvements within the broad scope of my 55 idea as set forth in the annexed claim.

I claim:

A device for the purpose described, comprising a symmetrical wire structure having angularly arranged suspension means, narrowing at their upper and widening towards 60 their lower ends, and adapted to straddle with their upper end a suspending element in the form of a nail, screw, rod or rope, a pair of crosswise arranged arms extending 65 from said suspension means and terminating

in elongated article engaging means in the form of jaws substantially parallel and extending transversely of the length of the device, and a connecting member in engagement with said suspension means extending in a substantially right angular direction to the length of said jaws, adapted to actuate the latter for the purpose of opening or closing, and keeping closed said jaws.

In testimony whereof he affixes his signature.

ERICH LEHR.
